US0D1100395S

(12) **United States Design Patent** (10) **Patent No.:** **US D1,100,395 S**
(45) **Date of Patent:** **** Oct. 28, 2025**

(54) **SIDE MOP FOR CLEANING ROBOT**

(71) Applicant: **Beijing Roborock Technology Co., Ltd.**, Beijing (CN)

(72) Inventor: **Yao Lu**, Beijing (CN)

(73) Assignee: **Beijing Roborock Technology Co., Ltd.**, Beijing (CN)

(**) Term: **15 Years**

(21) Appl. No.: **35/522,204**

(22) Filed: **Aug. 8, 2024**

(80) **Hague Agreement Data**

Int. Filing Date: **Aug. 8, 2024**

Int. Reg. No.: **DM/239573**

Int. Reg. Date: **Aug. 8, 2024**

Int. Reg. Pub. Date: **Sep. 6, 2024**

(51) LOC (15) Cl. **15-05**

(52) U.S. Cl.

USPC **D32/31**

(57) **CLAIM**

The ornamental design for a side mop for cleaning robot as shown and described.

DESCRIPTION

1. Side mop for cleaning robot

1.1 : Front

1.2 : Back

1.3 : Left

1.4 : Right

1.5 : Top

1.6 : Bottom

1.7 : Perspective

1.8 : Perspective

Reproduction 1.1 is a front view of a side mop for cleaning robot; reproduction 1.2 is a back view thereof; reproduction 1.3 is a left view thereof; reproduction 1.4 is a right view thereof; reproduction 1.5 is a top view thereof; reproduction 1.6 is a bottom view thereof; reproduction 1.7 is a top perspective view thereof; and reproduction 1.8 is a bottom perspective view thereof. The broken lines depict portions of the side mop for cleaning robot that form no part of the claimed design.

1 Claim, 8 Drawing Sheets
